BUCKLE OR CLASP FOR WATCH BRACELETS
AND THE LIKE

Charles H. Kestenman, Providence, R. I., assignor to Kestenman Bros. Mfg. Co., Providence, R. I., a corporation of Rhode Island

Application May 31, 1938, Serial No. 210,919

9 Claims. (Cl. 24—71)

This invention relates to improvements in buckles, clasps or connectors for watch-bracelets, and particularly to clasps of the extension type having articulated elements which fold one over another to contract the bracelet and fasten it to the wrist of the wearer.

One object of the invention is to provide positively-acting latching means for retaining the connected members of a clasp in closed or folded relationship.

Another object of the invention is to provide detent or latching means of the type indicated which provide greater security and must be manually released to unlock the folding elements.

Another object of the invention is to provide latching means which engage positively between the parts of the clasp in such manner as to prevent accidental release thereof under strain or stress to cause unwarranted opening or unfolding of the clasp.

Another object of the invention is to provide manually-operable means for releasing the latching means with ease and convenience.

Further objects of the improvement are set forth in the following specification which illustrates two preferred forms of construction of the invention, by way of example, as illustrated by the accompanying drawing. In the drawing:

Fig. 1 is a perspective view of a link-type bracelet attached to a wrist-watch with its ends joined by a folding clasp or connector embodying the present invention;

Fig. 2 is an enlarged plan view of the clasp shown with its cover partly broken away to more clearly illustrate the latching means;

Fig. 3 is a longitudinal sectional view of the clasp shown in Fig. 2 taken in a median plane;

Fig. 4 is a plan view illustrating the clasp with its parts in unfolded and extended relationship;

Fig. 5 is a longitudinal sectional view of the same taken in a median plane;

Fig. 6 is a bottom plan view of the clasp showing its parts in unfolded and extended relationship;

Fig. 7 is a plan view of the bottom member of the clasp illustrated partly in section to show the latches and the manually-operable releasing means therefor;

Fig. 8 is a transverse sectional view on line 8—8 of Fig. 2 showing the latches on the bottom member engaged with the cover member to hold the parts in folded relationship;

Fig. 9 is a similar view showing the latches released; and

Fig. 10 is a view similar to Fig. 7 showing a

modified form of construction of the latching means and manually-operable releasing means therefor as applied to a relatively narrow clasp for ladies' wrist-watch bracelets.

In accordance with the present mode, a popular type of wrist-watch bracelet embodies a linkage 2 connected to the sides of the watch 3, as shown in Fig. 1 of the present drawing, with the opposite ends of the bracelet joined by an ornamental clasp 5. One of the most popular clasps of this type is comprised of a plurality of articulated or hinged elements 6 and 7 which fold one upon another into a cover 10 as shown most clearly in Figs. 2 to 5. In certain instances the clasp may comprise still another extension member 12 15 which is slidable between the foldable members, for example, it may be telescopically mounted in the cover 10. Also, as herein shown, the slideable extension member 12 is provided with a spring-detent or pawl 13 adapted to engage with the 20 teeth 14 of a ratchet on one of the foldable members 7 when the parts are in closed relationship as illustrated in Fig. 3 of the drawing. The extension member 12 may thus be adjusted longitudinally of the clasp to regulate the length of 25 the bracelet to adapt it to fit snugly around the wrist of the wearer, while being released by the ratchet means when the clasp is opened or unfolded to further extend the length of the bracelet as a whole.

The several parts of the bracelet-clasp as thus far described are well known in the art and the present invention is applied to use therewith for positively latching or locking the foldable elements within the cover or upper member 10. For 35 this purpose I provide one or more spring-arms 15 mounted on one foldable element of the clasp and having latches 16 at their ends for positively engaging with detent means on another part. As illustrated in Figs. 2 to 9, a pair of spring-arms 40 15 are mounted on the bottom member 6 of the clasp with their latches constructed in the form of lugs or ears 16 projecting laterally through slots 17 in the upstanding sides of the member 6, see Figs. 4, 7 and 8. It will be noted by reference to these latter views that the bottom member 6 of the clasp is of channel form having a bottom plate 18 with upstanding side walls 19.

The spring-arms 15 are preferably made integral with a bifurcated plate-like element 20 constructed from spring-tempered sheet-metal. Folded upwardly from the sides of the arms 15 of the latch-element 20 are flanges 21 which extend rearwardly beyond the end of the bottom 55

plate of the element in ears 22. The upstanding flanges 21 abut the inner faces of the side walls 19 of the bottom member 6 and the ears 22 are pierced with holes for receiving the hinge-pin 23 which connects the bottom member 6 of the clasp with the intermediate folding element 7 which is similarly connected to the cover 10.

By this form of construction the latch-element 20 is permanently connected to the inner end of the bottom member 6 of the clasp while permitting its arms 15 to be sprung inwardly as shown in Fig. 7. The latches 16 are formed by laterally-projecting portions of the stock of the arms bent upwardly and then outwardly as shown more particularly in Figs. 8 and 9. The latches 16 project through the slots 17 in the side walls 19 of the member 6, as before indicated, thus holding the arms 15 flat against the bottom wall 18 of the member 6 while permitting free lateral movement of the arms.

Referring more particularly to Figs. 3, 8 and 9, when the hinged members 6 and 7 are folded into overlying relationship within the cover member 10, in the manner indicated by dash-lines in Fig. 5, the sides of the cover close down across the side walls 19 of the bottom member 6 as most clearly illustrated in Figs. 8 and 9. The cover member 10 is of substantially box-shape in cross-section with its side walls 24 folded inwardly at the bottom to form longitudinally extending flanges 25. The edges of the flanges 25 fit closely against the side walls 19 of the bottom member 6 when the several parts of the clasp are in folded or clasped relationship and the latches 16 on the spring-arms 15 are then adapted to slide outwardly to overlie the upper edges of the flanges 25 as shown in Fig. 8. It is also to be noted that the bottom edges of the flanges are beveled or rounded at 33 to adapt the latches 16 to snap across the flanges in the manner as later explained. By springing the arms 15 toward each other as shown in Figs. 7 and 9 the latches 16 may be withdrawn through the slots 17 in the side walls 19 of the bottom member 6 to release 45 their locking engagement with the flanges 25.

As an improved means for manually releasing the latches 16 to permit unfolding of the parts of the clasp, a slide 26 is provided on the member 6. The slide 26 takes the form of a flat plate, shown most clearly in Figs. 4, 5 and 7, which is connected to the member 6 by means of tabs 27 extending through slots 28 in the slide. The tabs 27 are constructed from portions of the metal cut away from the bottom plate 18 of the member 6 and bent up from the sides of the opening 29 thus formed, see Fig. 6. The tabs 27 project through the slots 28 and are bent over at right-angles to overlie the top of the slide 26 as illustrated most clearly in Figs. 4 and 5. At its inner end the slide 26 is formed with a V-shaped opening 30, the opposite sides of which provide inclined cam-faces adapted to engage against correspondingly-inclined angular edges 31 at the ends of the arms 15. It will thus be observed that when the slide 26 is slid longitudinally into the member 6 the angularly related faces of the opening 30 will cam against the inclined edges 31 on the arms 15 to spring the latter inwardly as illustrated in Fig. 7 of the drawing. The slide 26 projects outwardly beyond the end of the member 6 and has a narrowed portion which is rolled over to form a tubular ring or loop 32 for connection to the end of the bracelet. As shown in Fig. 5 the tubular end portion or loop 32 on the 75 slide 26 is hooked through the end link of the

bracelet 2 and closed together as illustrated in Fig. 5. The loop portion 32 thus serves as a finger-piece for pressing the slide 26 inwardly into the member 6 to release the latches to unlock the parts of the clasp while, normally, any strain on the bracelet tends to maintain the slide withdrawn from engagement with the arms 15 when their latches 16 are interlocked with the cover 10.

In applying the bracelet to or removing it from the wrist the present improved clasp operates as next explained. The bracelet is placed on the wrist by passing it over the hand while the several parts 6, 7, 10 and 12 of the clasp 5 are in extended relationship as illustrated in Fig. 5. Thereafter, the parts 6 and 7 of the clasp are folded into overlying relationship and swung into position within the cover 10, the latches 16 acting automatically to snap across the rounded edges 33 of the flanges 25 as the arms 15 are sprung inwardly from the sides 19 of the member 6. After the clasp has been closed in this manner the extension member 12 may be slid into the cover 10 to adjust the bracelet snugly around the wrist of the wearer. During this operation the pawl 13 on the extension member 12 slides over the ratchet-teeth on the member 7 and eventually engages the proper tooth to retain the extension member adjusted to the required position.

To remove the bracelet from the wrist the slide 26 is first slid into the member 6 by pressing the thumb or finger against its curled loop portion 32, this action causing the angular faces of the V-shaped opening 30 to cam against the inclined edges 31 of the spring-arms 15 to withdraw the latches 16 from engagement with the flanges 25 on the cover 10. With the cover released from the bottom member 6 the several parts of the clasp may be unfolded and as the member 7 is moved away from the cover it releases the pawl 13 to permit the member 12 to be extended longitudinally from the cover. It is also to be noted that the resiliency of the latch-arms 15 will cause them to spring apart immediately the pressure on the slide 26 is released by the operator and the cam-edges 31 at their ends will cam the slide outwardly of the member 6 into inoperative position. The manual operation of the clasp is thus extremely simple and convenient to accomplish while the latching means, because of its positive action, provides for greater security against accidental unclasping of the bracelet.

Fig. 10 illustrates a modified form of construction of the clasp which is particularly adapted for use on ladies' watch-bracelets. In this latter form of construction the bottom member 36 of the clasp is relatively narrow and to conserve space a single latch-arm 37 is employed. The latch-arm 37 is constructed integral with a plate member 38 of bifurcated form seated against the bottom wall of the member 36 and provided with upstanding flanges 39 and 40 which abut the side walls 41 thereof. The latch-element 38 is secured in position within the member 36 by a different form of construction from that previously described; the object being to eliminate ears at the hinge-joint between the member 36 and its connecting member 7 to avoid a reduction in the width of the bearing for the hinge-pin 23. The arm 37 has a latch 45 projecting laterally therefrom through a slot 46 in the side of the member 36 and on the opposite arm 37 is a similar projection 47 fitted to a narrower slot in the side wall of the member 36. At the opposite end of the latch-member 38 a lug 48 projects into an opening 76

in the side wall of the member 36, the two lugs 47 and 48 serving to secure the latch-member or plate 38 in position both longitudinally of and against upward movement on the member 36. As 5 a further means of fastening the latch-element 38 in place the metal of the side wall of the member 36 may be indented on the outside to form a projection 49 on its inner face overlying the top of the side flange on the latch-element.

10 In this last-described embodiment of the invention the slide 50 for releasing the latching means is of the same form as that previously described, except that its inward end is provided with a single angular cam-face 51 for acting 15 against the inclined edge 52 of the arm 37 which carries the latch 45. The method of operation of the last-described device is the same as with the device previously described, the slide 50 being slid into the member 36 to cause its angular cam-face 51 to act on the inclined edge 52 of the arm 37 to withdraw the latch 45 through the slot in the side wall of the member 36.

15 It will be observed from the foregoing that the present invention provides a novel and ingenious construction of latching means for positively locking the folding parts of a clasp in closed relationship while permitting convenience in releasing the latching means by simply sliding an element into the end of the clasp. The latching means is particularly adapted to prevent accidental unclasping of the bracelet, it being necessary to manually operate said means to release them and any strain or pull on the bracelet tends to hold the releasing slide in inoperative position.

20 It will also be observed that all the mechanical elements of the device are enclosed and concealed from view when the clasp is closed. Moreover, there are no projecting finger-pieces or levers on the outside of the clasp. In other words, one of the connecting parts of the clasp serves as the means for manually actuating the latch-releasing slide and thus the mechanical features, besides being unobtrusive, do not project from the sides or the end of the clasp in such manner as to be liable to scratch the wrist or catch in the garments of the wearer of the bracelet.

25 While the present improved device is herein illustrated in two preferred forms of construction, it is to be understood that certain changes may be made in the structure and arrangement of its parts without departing from the spirit or scope of the invention. Therefore, without limiting myself in this respect, I claim:

30 1. A clasp or connector for watch-bracelets and the like comprising a plurality of hingedly-connected foldable members, latching means for holding said members in overlying contracted relationship, and means at one end of the clasp for connecting it to the end of a bracelet, said means being mounted to slide longitudinally of the clasp and operative to release the latching means to permit extension of the members of the clasp.

35 2. A clasp or connector for watch-bracelets and the like comprising hingedly-connected members adapted to be folded into overlying contracted relationship, latching means for holding said members in contracted relationship, and a member 40 mounted to slide on one of the hingedly connected members and having means at one end thereof adapted for connection to the end of a bracelet, said member being slidable into the clasp and embodying means operative on the latching means to release the latter.

3. A clasp or connector for watch-bracelets and the like comprising a cover-member and a plurality of extension members hingedly connected thereto to fold into overlying relationship therewith, latching means on one of said members for 45 engaging with another of the members to hold said members in overlying relationship, a slide mounted at the end of one of the members to slide longitudinally thereof and formed to adapt it for connection with an end of the bracelet, 50 said slide having means thereon so constructed and arranged as to cause it to release the latching means when it is slid longitudinally of the member on which it is mounted.

4. A clasp or connector for watch-bracelets and the like comprising a plurality of interconnected members adapted to be folded into overlying relationship to contract the bracelet around the wrist, a resilient latch on one of the members adapted 55 to engage with another member to hold the several members in folded relationship, a slide 60 slideable on one of the members, and camming means between the slide and the latch adapted to release the latter when the slide is slid longitudinally of the member on which it is mounted.

5. A clasp or connector for watch-bracelets and the like comprising a plurality of hingedly-connected foldable members adapted to be contracted into overlying relationship, a resilient arm on one of the members having a latch 65 adapted to engage with another member to hold the several members in folded relationship, said arm formed with an inclined cam-face at its end, a slide 70 slideable on the member carrying the latch-arm and formed with a cam-face engageable with the cam-face thereof, said slide being slideable longitudinally of the member on which it is mounted to cause the cam-faces to release the latch from the member with which it is engaged.

6. A clasp or connector for watch-bracelets and the like comprising a cover-member and a bottom member with an intermediate member hingedly interconnected therewith to adapt the several members to be folded into overlying relationship, said cover member having a flange projecting inwardly from its side, a resilient latch carried by the bottom member and adapted to snap across the edge of the flange on the cover-member to hold the several members in folded 75 relationship, a slide slideable longitudinally of the bottom member, and camming means connected to the slide and the latch and operative to release the latter from engagement with the flange on the cover-member when the slide is slid longitudinally of the bottom member.

7. A clasp or connector for watch-bracelets and the like comprising a channel-shaped cover-member, a channel-shaped bottom member, an intermediate member hingedly connected to the 80 ends of the cover-member and bottom member to adapt said members to be folded into overlying relationship, said cover-member having an in-turned flange at its side forming a latching shoulder, a resilient arm fixedly mounted at one end within the bottom member and having a latching lug projecting through a slot in the side of the bottom member to adapt it to snap over the edge of the flange on the cover-member to hold the parts in folded relationship, said latch-arm 85 having an angular edge at its free end, and a slide slidably mounted within the sides of the bottom member and formed at its inner end with an angular face adapted to cam against the angular end of the latch-arm to move the latter 90

75

- to release the latch from engagement with the shoulder on the cover.
8. In a clasp or connector for watch-bracelets and the like, the combination of a channel-shaped cover-member having inturned flanges at the bottom of its sides, a channel-shaped bottom member having upstanding walls adapted to fit between the inturned flanges on the cover-member, an extension member hingedly connected to the ends of the cover and bottom member to adapt the several members to be folded into overlying relationship with the bottom member enclosed within the sides of the cover-member, a resilient arm abutting the bottom wall of the bottom member and formed with a latch at its end projecting through an opening in the side of the bottom member to adapt it to snap over the flange on the cover-member to latch the several members in folded relationship, said arm also having an upstanding flange secured to the side of the bottom member, a slide slidable within the sides of the bottom member, and camming means formed on the slide and the end of the arm and adapted to be engaged by movement of the slide longitudinally of the bottom member to cam the arm away from the side of the bottom member to release the latch from engagement with the flange on the cover-member.
9. A clasp or connector for watch-bracelets and the like comprising a cover-member of channel shape having inturned flanges at the bottom of its sides, a bottom member of channel shape having upstanding sides adapted to fit between the edges of the flanges on the cover member, extension means connecting said cover-member and bottom member to adapt them to be closed into overlying relationship, a bifurcated latching plate on the bottom member having a resilient arm with a latch at its end projecting from the side of the bottom member to adapt it to snap over the flange on the cover-member, lateral projections on the sides of the bifurcated plate engaging through openings in the sides of the bottom member to secure said plate in fixed position thereon while adapting the spring-arm to yield to withdraw the latch into the opening in the side of said bottom member, a slide slidable within the bottom member, and camming faces formed on the slide and the end of the latching arm adapted to be engaged by the sliding movement of the slide to move the arm to release the latch.

CHARLES H. KESTENMAN. 25
